UNITED STATES PATENT OFFICE.

CHARLES L. RAYFIELD, OF CHICAGO, ILLINOIS, ASSIGNOR TO BENEKE MANUFACTURING COMPANY, OF CHICAGO, ILLINOIS, A CORPORATION OF ILLINOIS.

CARBURETOR.

Application filed February 6, 1919. Serial No. 275,408.

To all whom it may concern:

Be it known that I, CHARLES L. RAYFIELD, a citizen of the United States, and a resident of the city of Chicago, in the county 5 of Cook and State of Illinois, have invented certain new and useful Improvements in a Carburetor; and I do hereby declare that the following is a full, clear, and exact description of the same, reference being had 10 to the accompanying drawings, and to the numerals of reference marked thereon, which form a part of this specification.

My invention has reference more particularly to a carburetor wherein the fuel is 15 maintained at several levels and supplied therefrom to the mixing chamber of the carburetor in such a manner so as to provide a variable mixture which is proportioned to afford a proper mixture to operate the engine.

The object of my invention is to provide a carburetor in which the proportion of the mixture is automatically varied by the draft or suction acting directly upon the fuel 25 liquid which is arranged in pockets or wells affording a differential supply of fuel liquid and which is introduced into the mixing chamber in such a manner so that the mixture is properly proportioned in accordance 30 with the requirements of the engine.

Another object of my invention is to provide a plurality of fuel compartments wherein the fuel is maintained at different levels, and ducts leading therefrom to the 35 mixing chamber so that the proportion of fuel drawn from the different chambers is regulated and proportioned by the suction in the mixing chamber so as to afford a mixture to accord with the requirements of the engine under the various conditions of 40 its operation.

Another object of my invention is to provide a carburetor with a plurality of fuel chambers, one of which is provided with a 45 float whereby the liquid is regulated in both chambers, and ducts leading from both chambers to the mixing chamber of the carburetor so as to supply varying amounts of fuel from the fuel chambers and proportion 50 the mixture properly in accordance with the requirements of the engine.

Another object of my invention is to provide a carburetor with a mixing chamber having a Venturi tube, and a plurality of

fuel chambers wherein the liquid fuel is 55 automatically maintained at different levels, and ducts leading from the fuel chambers and having the outlets therefrom positioned with reference to the Venturi tube so that the draft therethrough automatically varies 60 the amount of fuel drawn from the different fuel chambers so as to afford a mixture which is properly proportioned to accord with the requirements of the engine under 65 all conditions.

My invention also has other important objects which will be apparent from the disclosure in the specification and the accompanying drawings, in which I have shown and described my invention in a preferred 70 form.

On the drawings:

Figure 1 is a side view of the carburetor embodying my invention.

Figure 2 is a top view thereof.

Figure 3 is a sectional view on the line 3—3 of Figure 2.

Figure 4 is a vertical sectional view on the line 4—4 of Figure 2.

Figure 5 is a horizontal transverse sectional view on the line 5—5 of Figure 3.

Figure 6 is a transverse sectional view on the line 6—6 of Figure 3.

Figure 7 is a fragmentary sectional view on the line 7—7 of Figure 5.

Figure 8 is a fragmentary sectional view on the line 8—8 of Figure 5.

Figure 9 is an enlarged sectional view on the line 9—9 of Figure 7.

Figure 10 is a fragmentary sectional view on the line 10—10 of Figure 2.

Figure 11 is an enlarged top view of the fuel nozzle having the cross tube into which it communicates removed.

As shown on the drawings:

The reference numeral 1, indicates the carburetor casing which is formed with an air chamber 2, having a tubular extension 3, at one side thereof, with which an air inlet pipe 90, is connected, and a tubular extension 4, at the top thereof, provided with the usual flange 5, for connecting the carburetor to the intake pipe of the engine. Directly below the air chamber 2, is a chamber 6, which is separated from the mixing 100 chamber by the partition 7, which latter has a tubular internally threaded extension 8, thereabove and a similar internally threaded

extension 9, therebelow with an enlarged chamber 10, therein, all of which align with the tubular extension 4, at the top of the air chamber 2, and secured to the bottom of the casing 1, directly below and in alignment with the extensions 8 and 9, is a cup 11, which serves as a float chamber for the float 12.

A Venturi tube 13, is located in the outlet extension 4, from the air chamber 2, and immediately above this tube there is a butterfly valve 14, which is mounted on the stem 15, extending through bearings provided therefor on the under side of the flange 5, and there is a crank 16, on one end of the shaft 15, which may be connected for operation from a distance to control the opening and closing of the valve 14.

At one side of the air chamber 2, the casing 1, is formed with an auxiliary fuel compartment 17, which is separated from the chamber 2, by the partition 18, and from the fuel chamber 6 by the wall 19, which latter wall has a threaded hub 20, which is adapted to have the sleeve 21, screwed therein so as to project upwardly through the auxiliary chamber 17, to a point adjacent the top wall thereof. The wall 22, of the float feed chamber, directly below the partition 19, has an enlarged threaded opening through which the sleeve 21, may be inserted, and this opening is closed by a threaded plug 23. The side wall 18, of the auxiliary chamber 17, has a passageway 24, extending upwardly therethrough, the upper end of which opens to the auxiliary chamber 17, at a point near the upper wall 25, of this chamber, and the lower end thereof opens into the float feed chamber 6, and this passage serves as an overflow outlet for the auxiliary chamber 17, and is also the means of supplying fuel to the float feed chamber 6, so that the auxiliary chamber 17, must be filled before fuel is supplied to the float feed chamber 6.

The upper wall 25, of the auxiliary chamber 17, has a fuel inlet passageway 26, leading from the interior of the threaded hub 27, which latter has the bushing 28, connected therewith, and the bushing has the fuel supply pipe 29, connected therewith and communicating therethrough so as to supply fuel to the passageway 26. An opening 30, leads downwardly from a point adjacent the inner end of the passageway 26, in alignment with the opening through the sleeve 21, so that the upper tapered end 32, of the valve pin 31, which slides loosely in the sleeve 21, may engage in the lower end of the opening 30, to control the supply of fuel therethrough.

The stem 31, and valve 32, thereof, is operated to control the admission of fuel through the opening 30, by the float 12, by means of the plate lever 33, which is piv-

oted at 34, and extends under and engages the lower end of the pin 31, and has the outer end forked and the arms 35, thereof, resting upon the top of the float 12, so that when the float is elevated by raising of the level of liquid in the fuel chamber 6, the plate lever 33, is swung on the pivot 34, and lifts the stem 31, so that at a predetermined lever the tapered end 32, of the stem engages the fuel supply opening 30, so as to interrupt further supply of fuel to the carburetor.

Obviously the fuel supplied to the float chamber 6, must overflow from the auxiliary chamber 17, and therefore the chamber 17, is filled before fuel is supplied to the float feed chamber 6, and when the float 12, is raised to the level to close the valve 32, the float feed chamber will be filled to the predetermined level and the auxiliary chamber 17, will also be filled to the level at which it overflows. In order to afford free circulation of fuel to and from the auxiliary chamber 17, an air port 36, is provided in the upper wall of the auxiliary chamber 17, and there is also a similar port 37, in the wall 7, intermediate of the air chamber and the float feed chamber 6, and likewise a port 38, leading from the top of the float feed chamber, through the side wall to the exterior of the carburetor. The port 37, however, serves primarily as a drainage outlet from the air chamber 2, for any liquid that may drain to the bottom of the air chamber from the nozzle, and there is a lip 39, extending from the bottom of the air chamber at the outer side thereof from the port 37, to retain any unused fuel in the air chamber so that it may drain through the port 37, into the float feed chamber.

For connecting the cup 11, which contains the float 12, with the casing 1, there is a tubular stem 40, the upper end of which has a threaded connection with the tubular extension 9, from the wall 7, and forms a closure for the bottom of the chamber 10, and this tubular stem 40, extends downwardly loosely through a central opening in the float 12 formed by a hub 41, which extends axially through the float, and the lower end of the tubular stem 40, passes through an opening 42, in the bottom of the cup member 11, and has the cap 43, threaded thereon against the washer 44, which engages the bottom of the cup 11, thus sealing the joint between the cup and tubular stem and forcing the upper edge of the cup 11, tight into the annular seat 45, provided therefor in the carburetor casting 1.

A bushing 46, is threaded into the extension 8, above the wall 7, and a nozzle 47, is threaded into the upper end of the bushing 46, and extends upwardly therefrom, so that the upper end of the nozzle is located in the Venturi tube 13, and slightly above the

throat thereof, the said nozzle 47, being flared outwardly at the upper end to provide a contracted passageway between the nozzle and the throat of the Venturi tube so as to effect an increase in suction above the upper end of the nozzle. The nozzle 47, together with the bushing 46, closes the upper end of the fuel chamber or well 10, which is provided in the partition 7, and there is a tube 48, which makes a close fit in an opening at the upper end of the nozzle 47, and projects a very slight distance thereabove, and this tube extends downwardly through the well 10, and through the upper end of the tubular stem 40, to which it is secured for support and to make a tight joint and extends downwardly through the enlarged passageway 49, of the tubular stem 40, to a point adjacent the bottom of the cup 11. A plug 50, closes the lower end of the tube 48, and there are a plurality of openings 51, into the tube above the plug to admit fuel thereto. The opening 49, through the tubular stem 40, is larger than the outside diameter of the tube 48, so as to provide space for fuel therebetween, and there are a plurality of ports 52, leading into the interior of the tubular stem 40, adjacent the bottom of the cup 11, to supply fuel thereto, and there is an air port 53, at the top of the chamber 49, to avoid pocketing of air in the tubular passageway 49, so that the fuel therein is maintained at the same level as in the cup 11.

The nozzle 47, is bored out, except at the upper extremity thereof to a larger diameter than the outside diameter of the tube 48, so as to provide an annular passageway 54, for fuel from the well 10, the diameter of the upper end of this opening being reduced so that the tube 48, fits snugly therein and there are a plurality of diverging passageways 55, leading from the upper end of the annular passageway 54, into an annular groove 56, with which the upper end of the nozzle is provided. Ports 57, are provided in the nozzle leading outwardly from the annular passageway 54, to a point below the Venturi tube 13, and above the level at which the fuel is maintained in the well 10, and passageway 54.

Fuel is supplied to the well 10, from the auxiliary fuel chamber, through the passageway 58, which is bored in the casing 1, and has the outer end thereof closed by means of the plug 59, and there is an opening 60, leading upwardly from the passageway 58, and communicating with the fuel chamber 61, which chamber extends laterally from and is connected at the bottom of the auxiliary chamber 17. The supply of fuel through the port 60, is controlled by the valve 62, which is tapered at the lower end to engage in the upper end of the port 60.

The stem of this valve is threaded at 63, and engages in the wall of the casing above the chamber 61, so that when the stem is turned in one direction, the valve is closed and when turned in the other direction is elevated from the opening 60, and affords a limited passage for supplying fuel to the passageway 58, and well 10. For operating the stem 62, there is a crank 64, at the upper end thereof, which may be connected by means of a Bowden cable 65, or in other manner, for operation from a distance, and this crank 64, has a long hub 66, which extends downwardly around the stem in a tubular opening provided therefor in the carburetor casing, and serves to control an auxiliary fuel passage as hereinafter noted.

In the normal operation of the carburetor, the crank 64, is moved to open the valve 62, a slight amount, and may be adjusted to regulate the supply of fuel to the well 10, to effect the desired operation of the motor, or may be entirely closed. To enable the contents of the well 10, to be exhausted therefrom when the valve 62, is closed, there is a vent passage 67, leading upwardly from the outer end of the passageway 58, and having an air opening 69, at the upper end so that liquid may be drawn from the well 10, without creating a vacuum therein.

Extending transversely across the Venturi tube 13, is a cross tube 70, which has an opening in the under side thereof adapted to receive the upper end of the tube 48, therein to admit fuel into the tube 70, from the pipe 48, and there is an opening 71, in the lateral wall of the tube 70, through which the fuel is normally supplied to be mixed with the incoming air. A stem 72, is threaded through the wall of the casing into the end of the tube 70, and has a tapered end 73, which serves to obstruct the opening 71, to a greater or less extent and thereby control the supply of fuel furnished through the pipe 70. The stem 72, has a thumb nut 74, on the outer end, the serrated periphery of which is engaged by a spring detent 75, secured to the casing of the carburetor, and which permits turning of the stem and holds the thumb nut 74, in any position to which it is adjusted. The other end of the tube 70, communicates with a passageway 76, which leads therefrom upwardly through the wall of the tubular extension 4, of the carburetor, and has an outlet 76, at the upper end opening into the carburetor outlet above the throttle valve 14, so that when the throttle is closed, or nearly closed, the fuel may be supplied above the throttle valve.

To furnish a supply of fuel for priming the engine, at which time the throttle valve is usually opened only a limited degree, there is a passageway for fuel leading from the bottom of the float feed chamber to a

- point above the throttle valve, and controlled by the position of the crank 64, so that this passageway is normally closed but may be opened for priming purposes by
- 5 moving the crank to the extreme right from the position shown in Figure 2. For this purpose, the sleeve or hub 66, with which the crank 64, is provided, has an arcuate groove 77, located therein in such position
- 10 that when the crank is moved to the extreme right from the position shown in Figure 2, one end thereof communicates with a passageway 78, which leads downwardly and is connected by means of the pipe 79, with
- 15 an offset chamber 80, at the bottom of and connected with the float feed chamber 6, so that fuel is supplied thereto from this chamber. The other end of the groove 77, when the crank 64, is in the priming position, communicates with the passageway 81, which communicates with an upright passageway 82, in the wall of the tubular extension 4, of the carburetor, and has an opening 83, therefrom to the outlet from the carburetor
- 20 25 above the throttle valve 14. As will be noted, when the hub 66, and groove 77 are in the position shown in Figure 9, in which the crank 64, is moved to the extreme right from the position shown in Figure 2, they afford communication between the passageways 78 and 81. When, however, the crank 64, is moved back towards the original position, communication is interrupted with the passageway 81, and there is an air port
- 30 35 40 45 50 55 60 65 70 75 80 85 90 95 100 105 110 115 120 125 130
- 84, with which the end of the slot 77 comes into communication when the crank 64, is moved to the position substantially as shown in Figure 2, or that which is occupied by the valve in normal operation of the carburetor, and as the groove 77, is continuously in communication with the passageway 78, in closing the valve 62, the groove 77, will register with the port 84, and provide air release to the passage 78, and permit the fuel liquid to return to the normal level.
- The operation is as follows:
- The carburetor is connected by means of the attaching flange 5, so that the extension 4, communicates with the intake pipe of the engine, and the pipe 90, may lead to any convenient point to supply clean air to the carburetor, and the fuel supply pipe 29, is connected with a source of supply to maintain a constant supply of fuel to the carburetor. As the fuel enters through the port 30, the auxiliary chamber 17 is filled to the upper extremity of the passageway 24, during which time the air is exhausted from the chamber 17, through the port 36, and also through the passage 24, and after the fuel reaches this level, it overflows through the passage 24, into the float chamber 6. When the liquid reaches a predetermined level in the float chamber, the float is elevated thereby and with it the plate lever
- 33, which swings upwardly on its pivot and lifts the stem 31, which constantly rests on the top of the plate lever 33, and projects the point 32, of the stem into the opening 30, and interrupts communication of fuel therethrough, and as the fuel is used from the float feed chamber 6, the float operates to automatically furnish fuel and maintain the same at a predetermined level and maintain a constant level of fuel in the auxiliary chamber 17.
- When it is desired to start the motor, the valve 14, is preferably adjusted so that the passage through the extension 4, is partially closed, and the crank 64, is moved to the right from the position shown in Figure 2, so that the slot 77, in the hub or sleeve 66, affords communication from the passageway 78, to the passageway 81. As the motor is turned over or cranked, suction is created in the outlet extension 4, and the draft through the air chamber 2 and Venturi tube 13, which is limited owing to the partially closed position of valve 14, draws a limited amount of fuel upwardly through the annular passageway 54, and out through the passageways 55, above the throat of the Venturi tube where it is mixed with the incoming air. Owing to the contraction of the mouth of the Venturi tube and the partial closing thereof by the upper end of the nozzle 47, a greater suction ordinarily exists above the throat of the Venturi tube than in the chamber 2, and air is drawn through the ports 57, into the annular passageway 54, together with the gasoline from the well 10, which serves to offset to some extent the suction effect on the gasoline in the well and furnishes the same through the annular passageway 54, in a spray which leaves the port 55 in a finely atomized condition so as to thoroughly mix with the incoming air and form a uniform mixture.
- As the throttle 14, is partially closed a partial vacuum is formed above the throttle valve 14, which lifts liquid fuel up through the pipe 79 and passageway 78, from the off-set chamber 80, at the bottom of the float feed chamber, and from the passageway 78, around the groove 77, and through the passageways 81 and 82, into the outlet opening from the carburetor above the throttle valve 14, where it is mixed with the air and fuel mixture which is being drawn past the valve 14. Fuel may also be supplied at such time above the throttle valve through the passageway 76, from the cross tube 70, in the Venturi tube, such fuel being drawn up through the tube 48, from the bottom of the float feed chamber. If the throttle valve 14, is closed sufficiently so that the suction above the throttle valve exceeds that immediately therebelow, the gasoline is introduced through the passageway 76, and discharged above the throttle valve and when

so operating, air is drawn through the opening 71, from the chamber in the Venturi tube and mixes with the gasoline drawn through the tube 48, so that a mixture of air and gasoline is introduced through the passage 82, above the throttle valve. Obviously the amount of fuel supplied through the passageways 76 and 82, above the throttle valve depends upon the position of the 10 throttle valve, a greater amount being supplied as the throttle valve nears the closed position, and as the throttle valve is opened a point is reached where the suction above the throat of the Venturi tube and below the 15 throttle valve is the same as that above the throttle valve, whereupon supply of fuel through the passage 76, is discontinued and the fuel is drawn directly from the tube 70, through the side outlet 71.

20 The adjustment of the crank 64, to permit passage of fuel through the arcuate slot 77, opens the valve 62, sufficiently to keep the well 10, filled with fuel, so that it may readily be drawn up through the annular 25 passageway 54 in starting the motor, and we have therefore three sources of supply of fuel for starting the motor or at such other time as the crank 64, may be moved to the priming position to afford a rich 30 mixture.

After the engine is started the crank 64, is moved to the left to the position shown in Figure 2, thereby interrupting communication from the passageway 78 to the passageway 81, which passageways supply fuel above the throttle valve, and the valve 62, may be entirely closed or adjusted to permit a limited supply of fuel to the well 10, to afford whatever mixture is necessary to operate the motor. If the valve 62, is entirely closed the level of fluid in the chamber 17, is of course maintained at the normal level by the float 12, and because of the vent passageway 67, fuel may be drawn from the well 10, until it is reduced to a level at which the suction is insufficient to withdraw a further supply therefrom, whereupon the fuel for the carburetor is supplied entirely from the float feed chamber through the tube 48. However, in the normal operation of the device, the valve 62, is adjusted to permit a limited supply of fuel to pass through the opening 60, to the well 10, the adjustment thereof determining the amount 55 of fuel which will be supplied through the annular passageway 54, and through the ports 55, at the top of the nozzle, and operates in conjunction with the float feed chamber to supply fuel for normal running 60 of the engine. Inasmuch as the level of fuel in the well 10, is near to the top of the nozzle, an abrupt opening of the valve 14, creates a suction in the upper portion of the Venturi tube above the nozzle to augment 75 the supply of fuel from the well 10, so as

to afford immediately the rich mixture required by the engine when its throttle is suddenly opened.

From the foregoing it will be observed that a supply of fuel is furnished from two sources, namely the fuel well 10, and the float feed chamber 6, the amount of which supplied from the former may be regulated by the needle valve 62, and the proportions of which vary with the speed of the engine and also the opening of the throttle valve so that the proper mixture may be obtained at all times, as required under the varying conditions of operation of the engine, and it will be further noted that as the throttle valve is moved to the closed position the passage 76, serves to admit fuel above the throttle valve to furnish a rich mixture for slow speed or idling speed.

While I have shown and described my invention in a preferred form, I am aware that various changes and modifications may be made therein without departing from the principles of my invention, and I therefore do not purpose limiting the patent granted hereon otherwise than necessitated by the prior art.

I claim as my invention:

1. In a carburetor the combination of a casing having a mixing chamber, an air inlet thereto, a fuel chamber, a fuel well, an outlet from the fuel chamber and from the fuel well to the mixing chamber, an auxiliary fuel reservoir through which fuel is supplied to both chamber and well, a float for maintaining a uniform supply of fuel in the fuel chamber, and a manually adjustable valve for regulating the supply of fuel from the auxiliary fuel reservoir to the fuel well.
2. In a carburetor a float chamber, an auxiliary fuel chamber communicating with said float chamber, a fuel well at a higher level than said float chamber and communicating with the auxiliary fuel chamber, and a multi-passaged nozzle extending through and having separate passages respectively in communication with said well and float chambers.
3. In a carburetor the combination of a casing having a mixing chamber and an air inlet thereto, a float chamber and a fuel well each having an outlet to the mixing chamber for supplying fuel thereto by aspiration, an auxiliary fuel chamber for supplying fuel to the fuel well and having an overflow passageway discharging into the float chamber, and a float in the float chamber for controlling the supply of fuel to the auxiliary fuel chamber.

4. In a carburetor the combination of a casing having a mixing chamber and an air inlet thereto and an outlet therefrom, a throttle valve in the outlet, fuel supply means including a float chamber and having an outlet into the mixing chamber for

- supplying fuel by aspiration thereto, a fuel well having an outlet to the mixing chamber and an inlet with a manually controlled valve for maintaining a supply of fuel
5 therein at a higher level than the fuel in the float chamber, and a fuel by-pass for supplying fuel to the carburetor outlet above the throttle valve controlled by the aforesaid valve so that the by-pass is opened
10 simultaneously with the opening of the valve to admit fuel to the fuel chamber.
5. In a carburetor a throttle, two constant level fuel chambers maintaining fuel at different levels, a fuel well, a passage
15 feeding said well from the chamber maintaining the higher level, a fuel duct delivering below the throttle from said well, and

a fuel duct delivering above the throttle from the chamber maintaining the lower level.

20

6. In a carburetor a throttle, two constant level fuel chambers maintaining fuel at different levels, a fuel well, a passage feeding said well from the chamber maintaining the higher level, a fuel duct delivering below 25 the throttle from said well, a fuel duct delivering above the throttle from the chamber maintaining the lower level, a valve controlling said duct, and a common operating means 30 for said valves.

In testimony whereof I have hereunto
subscribed my name.

CHARLES L. RAYFIELD.
